UNITED STATES PATENT OFFICE

ANDREW YAKUNIN, OF CALGARY, ALBERTA, CANADA

HERMETICALLY-CLOSING-UP DEVICE FOR CARS

Application filed June 8, 1929, Serial No. 369,355, and in Canada May 2, 1929.

The invention is illustrated in the accompanying drawings, in which:

Figure 1 is a vertical sectional view of a tank car showing the apparatus mounted therein.

Figure 2 is a vertical sectional view of the valve.

Figure 3 is a section on the line 3—3 of Figure 1.

10 The tank car is illustrated diagrammatically at 1, being provided at an appropriate point with an outlet in the form of an extension 18 formed in its upper portion with a valve seat 19 and in its lower portion with 15 a valve seat 20, with a cylindrical portion 21 intermediate the respective valve seats.

An upper valve 5 is designed to cooperate 20 with the upper valve seat 20, this valve being formed to accurately fit throughout on the seat to insure a sealing cooperation between 25 the valve and seat. The valve 5 is provided with guide fingers 22 which more or less accurately fit the cylindrical portion 21 of the extension 18 to guide the valve 5 in movement. The valve 5 has a depending valve 30 stem 6 preferably connected to the valve through the medium of an eye and a transverse pin 24, so that some play is permitted the stem relative to the valve without, however, permitting relative endwise movement.

The valve seat 20 is preferably of the conical type, and a valve 7 is shaped to accurately cooperate with the valve seat 20, this valve 7 having a threaded longitudinal bore 35 25 to cooperate with the threaded portion 26 of the valve stem 6.

The valve 5 has an extension 27 to which 40 a valve stem 8 is connected through the medium of an eye 28 on the valve stem to permit a limited play between this upper valve stem 8 and the valve 5. The valve stem 8 is of a length to extend adjacent the man-hole or inlet of the tank car, indicated at 29, and in order to prevent the upper valve stem 8 from 45 being affected by jars of the vehicle or agi-

tation of the contained fluid during the travel of the vehicle, this upper valve stem is encircled by a sleeve member 10 supported at the upper end on braces 13 extending from the sides of the tank car and guided at the 50 lower end in braces 14 also extending from the tank car.

The upper end of the sleeve guard 10 provides or is formed with an abutment 12 on which a nut 9, arranged for threaded cooperation with the upper valve stem 8, is adapted to bear. If desired, the abutment 12 may be in the form of a nut engaging the upper 55 end of the sleeve and resting upon the upper brace 13, there being a further nut 11 engaging in the sleeve and resting in the lower brace 14, thus providing for more or less rigidly supporting the sleeve in order to protect the upper valve stem from undue movement.

60 The outlet formed in the extension 18 is designed to be closed by a cap 4 formed for threaded cooperation with the exterior of the extension, as more particularly shown in Figure 1 of the drawings.

65 It will be apparent that the closure of this invention includes two oppositely acting valves, both sealing the same outlet and one acting not only as a valve but as a means for preventing unsealing movement of the other. 70 It is quite apparent that as long as the valve 7 is not connected to the lower valve stem 6, the valve 5 may be raised and lowered by operation of the nut 9 but that when the valve 5 has been lowered to its seat, and the valve 7 thereafter applied to the lower valve stem 6 and tightened to its seat, the valve closures are complete and the outlet from the tank is hermetically sealed. When desiring 75 to open the outlet, the valve 7 is removed from the lower valve stem, whereupon the valve 5 may be raised by operation of the nut 9 to permit discharge of the contents of the tank car.

What is claimed to be new is:

A tank car or the like formed with an outlet having inwardly converging upper and lower valve seats, a valve cooperating with the upper seat, a stem depending therefrom, 5 a valve adapted to be threaded on said stem and having wedging cooperation with the lower seat, a valve stem for the upper valve, a cylindrical guard for the stem arranged within the tank car, and a nut threaded on the upper stem and supported on the guard for adjusting the position of the upper valve.

10 City of Calgary, May 2nd, 1929.

A. YAKUNIN.
